James P. Baxter of Portland, Maine

Letters Patent No. 2184. Dated Octo 10-1865.

Design for a Trade-Mark

The schedule referred to in these letters Patent and making part of the same.

It all which is may concern:

In witness whereof James P. Baxter, of

the City of Portland, County of Cumberland and State of Maine, have originated and designed a new design for a trade mark, of which the following is a full, clear and exact description, reference being had to the accompanying specimens or drawings making part of this specification.

My design consists of a ear of corn in color with bush striped back which shows the kernel or grain. Around this is an oval band also colored, on the outward edge of which are eight points. This oval band bears the words Yarmouth Sugar Corn Portland Packing Co. The words Yarmouth Sugar Corn being separated from the words Portland Packing Co. by two stars of five points each. Outside the oval band is a square border bearing in the four corners shaded scroll work, as shown in the accompanying drawings.

What I claim as my invention and would secure by letters Patent is the design for a trade mark as shown and described.
